UNITED STATES PATENT OFFICE.

HUDSON MAXIM, OF LONDON, ENGLAND.

WAR VESSEL.

SPECIFICATION forming part of Letters Patent No. 695,108, dated March 11, 1902.

Application filed November 10, 1898. Serial No. 696,102. (No model.)

To all whom it may concern:

Be it known that I, HUDSON MAXIM, a citizen of the United States, and a resident of London, England, now temporarily residing 5 at New York city, New York, have invented certain new and useful Improvements in War Vessels, of which the following is a full, clear, and exact description.

The present invention relates to war vessels and to methods and apparatus for handling and controlling the same.

The invention has particular reference to light torpedo-boats for the projection of aerial and submarine torpedoes and the firing of 15 other missiles.

The object of the invention is mainly to provide a torpedo-boat which shall have all its vulnerable or vital parts located deep beneath the water when in action and when 20 not in action may be quickly raised to such height with reference to submergence as to enable it to travel through the water with minimum resistance and maximum of speed and which may also at will be as quickly 25 submerged, but which when submerged shall present above the surface a comparatively fragile and wholly dispensable structure or superstructure which shall serve the purpose of flotation to prevent the vessel from sinking 30 too low beneath the surface and which in itself may also serve as a means for absorbing the impact of a missile striking the boat, so that the protective deck is in no danger of being struck.

35 The invention furthermore provides means for mounting its armament upon hydraulic platforms which may be raised quickly into position and water admitted simultaneously as ballast and the consequent lowering or submerging of the vessel, and which platforms may be quickly lowered, and thereby expel the water ballast to lighten and raise the ship and the armament itself serve as ballast when the ship is lightened or raised for the purpose of high speed.

In carrying out the invention a torpedo vessel is made or may be made on substantially the same lines as such craft are now constructed. A whaleback or curved deflecting 40 arm or shield is made to cover or to constitute the primary deck and which is interposed between the vital portions of the ves-

sel and the non-vital portions of the superstructure. Upon this protective deck, which may be of any desired thickness—say one 55 inch of nickel-steel—is erected a non-vital superstructure, preferably approximating the vessel proper in width, length, and shape. The superstructure is made to consist, preferably, of a large number of compartments 60 or cells separated by thin metallic partitions and the compartments or cells preferably filled with cork or other light or similar substance. The superstructure is made of such vertical height or depth as shall permit of the 65 shield-deck and the vital covered portions of the vessel being submerged a desired or required distance beneath the surface of the water—say from five to ten feet—leaving a sufficient amount of the superstructure above 70 water to present free board enough to provide against the wash of the sea. The funnels and ventilating and air pipes, &c., are made to pass through the superstructure, but which may be cut to pieces with shot and 75 shell without inflicting any vital injury upon the vessel or seriously impeding its functions.

When employed for launching Whitehead or other submarine torpedoes, the vessel when submerged to the desired depth may 80 be and is run directly through the fire from quick-firing guns from a battle-ship to launch its torpedo in close proximity to the battle-ship without suffering serious damage. The larger guns on the battle-ship cannot be depressed sufficiently to throw a projectile downward by plunging fire through the superstructure and shield-deck. Larger shell can only pass harmlessly through the superstructure, or, if bursting within it, the fragments will not possess destructive effect or force enough to reach downward to and through the shield-deck, and thus the entire superstructure may be shot away without material injury to the vital parts of the torpedo-boat and its mechanism. The smaller quick-firing guns, such as are employed against torpedo-boats, would not be powerful enough to pass through the superstructure and the shield-deck.

100 Circular vertical openings are provided through the superstructure for the emergence of aerial-torpedo-gun platforms or for pits for aerial-torpedo mortar fire. The hydraulic

platforms, with the torpedo-gun, are preferably a little heavier than the water displaced by them, so that they are raised into position by steam, air, or other power; but the weight of the platforms in the water may be nearly balanced, so that little power may be required for the purpose, and as soon as the power is removed or allowed to exhaust the platforms will descend automatically. In addition to the admission and displacement of water ballast by the raising and submergence of the gun-platform a certain additional amount of water ballast may be admitted and ejected in any suitable manner, but preferably by the contraction and expansion of air-chambers containing air under pressure and such pressure as to nearly balance the amount of water desired to be displaced by them in much the same manner as the swimming-bladder of fishes is contracted and expanded for the purpose of raising or lowering the fish in the water. These air-chambers are provided with means for contracting and expanding them and which, owing to the pressure of the contained air, will require but little additional power to obtain the maximum admission and ejection of the water-ballast.

Reference is to be had to the accompanying drawings, forming a part of this specification, in which drawings—

Figure 1 is a longitudinal vertical sectional view of a vessel provided with the invention. Fig. 2 is a horizontal section of the same, taken on a plane below the protective deck. Fig. 3 is a longitudinal vertical section of the same. Fig. 4 is a detail view of automatic devices controlling certain of the valves, and Fig. 5 is a detail of the sliding joint between one of the valve-stems and the beveled gearing for actuating it.

Referring to said drawings, the vessel A may be of any usual or preferred construction embodying a main body B, having the usual protective or shield deck C of, say, turtle or whale back form, the body being adapted to contain the usual steaming, propelling, and other facilities common in the class of vessels to which this invention more particularly relates, and in addition thereto carrying the armament and its mechanism and its ballast tanks or chambers, hereinafter described. The main body B supports a superstructure D of substantially the same length and width of the vessel, formed of thin metal and provided, preferably, with a number of compartments or cells e, adapted to contain and be filled with cork or other like material for flotation purposes, and also serving as an absorber of the impact of the missiles which may strike the vessel. This superstructure may, as indicated in Fig. 1, be detachably secured to the main body B, such detachability being represented by the screw-bolts y, operated from the interior of the main body of the vessel. The superstructure is pierced with a vertical hole or holes f

to permit the vertical movement of the gun-platforms g from their normal down position out of action into their raised active position and with a like hole or holes f' for the connecting-tower G, as in Fig. 3. The gun platform or platforms g, with the guns and casements h, are preferably arranged so that as they are raised into active position water will be simultaneously admitted to fill the space below them to materially aid in raising the platforms and when raised serving as a partial support therefor and also as a water ballast to hold the vessel submerged to the desired depth, as indicated in Fig. 1, so that the main body or vital portions of the vessel are removed from danger. As shown, the gun-platforms form pistons and move in a vertical hydraulic cylinder i, arranged for telescopic movement in a fixed hydraulic cylinder k, supported on the vessel's bottom, with sea-openings through the bottom for the free ingress and egress of the water to the cylinders and under side of the platform-piston. 90

Any proper means and power may be employed to cause the raising movement of the gun and platforms. Thus there is shown an arrangement of telescopic air-cylinders and piston m located centrally with the hydraulic cylinders, compressed air being admitted beneath the piston from any suitable engine E. When it is desired to lower the gun-platforms, as in Fig. 3, the air may be exhausted from the air-cylinders, so as to allow the weight of the platforms in lowering to expel the water ballast, and thus allow the vessel to rise up toward its normal or running water-line x, which platforms and their armament when in their down position then act as ballast for the vessel.

In addition to the water ballast admitted to the hydraulic-gun-platform cylinders water ballast may be received by any suitable chambers or water-compartments. Thus on one side 110 of the vessel, Fig. 2, there is shown a water-compartment F, controlled by a sea-valve o, by opening which the compartment may be filled, a pump p being provided to expel the water therefrom when desired. On the other side 115 of the vessel there is shown a chamber q in the form of a cylinder having a piston r, one side open to the sea and the other side to a confined body of air and connected to a hydraulic ram s, which aids in drawing the piston in one direction to compress the air to the maximum, and thus draw in the full quantity of water, and in the reverse direction to expel the water to the fullest extent after the compressed air has performed its duty in moving 120 the piston r in that direction.

While the gun-platforms are shown raised to their maximum, it is of course obvious that they need not be, as when in firing mortars their necessary elevation will be sufficient to 130 have their missiles clear the superstructure.

In addition to the disappearing gun-platforms and guns the vessel, as shown in Fig. 3, may be provided with a disappearing con-

ning-tower G, operated, say, by a telescopic pneumatic cylinder and piston t, air being supplied to said cylinder by any suitable engine, such as the engine E. The conning-tower of course may be and preferably is raised independent of the gun-platforms, the officer in the tower controlling the movements thereof, if preferred.

The war vessel may furthermore be adapted to be employed as a wholly-submerged craft by closing the hatchways and ports or other openings in the main or whaleback deck to make them water-tight, so that the boat may be driven under water at any desired depth either by steam or other motor fluid used expansively or by electricity. When the boat is entirely submerged, it is kept at a desired depth below the surface by the action of the pressure of the surrounding water. As the boat sinks to greater depths, the pressure of the water becoming greater, the excess of pressure below the line of travel or the horizontal plane on which the boat is traveling, as shown in Fig. 4, may be utilized to operate a valve or electrical switch u or other device for lessening or increasing the water ballast, either by actuating or causing the actuation of a hydraulic ram or by turning on steam or compressed air or other motor fluid or for operating an electric switch to actuate a pump p' for compressing or supplying more air into any of the chambers F for the expulsion of water or for pumping water out of the chambers. Hence by the operation of the controlling apparatus for regulating the depth of submergence of the boat the boat may be automatically maintained at the desired depth below the surface. The switch u is shown connected to a plunger v, one end exposed at the vessel's side or bottom to the sea, the pressure of the water imparting the desired movement thereto.

The electric motor J, operating the pump p' for discharging the water ballast from the compartment F, has its armature-shaft connected to the pump-driving pinion by a one-way clutch 10 of well-known form, so that upon the reversal of the motor the pump will remain idle. The reversal of the motor when the pressure of the water upon the switch-operating plunger v decreases, so that the switch may reverse the electric current to the motor, may operate to open the sea-valve o, so that water may enter the compartment. The connection of the bevel-gearing with the sea-valve stem is had by a friction-joint between the stem and its gear, permitting the longitudinal movement of the stem through the gear when the valve is being opened or closed and also permitting the motor to move the valve to its opened or closed positions irrespective of the continued operation of the motor.

While particular forms of mechanism have been shown, it is to be understood that the invention is susceptible of many modifica-

tions in details and arrangements of parts without departing from its scope.

What is claimed is—

1. In a vessel the combination of the main hull, a flotation superstructure secured water-tight upon the main hull, ballast-cylinders formed in the main hull and communicating with the open sea, pistons working in said ballast-cylinders, and power devices for operating said pistons, whereby the main hull may be maintained at the sea-level or depressed below the same as desired. 70

2. In a vessel the combination of the main hull provided with a protective deck, a cellular flotation superstructure secured water-tight upon the main hull, fixed ballast-cylinders formed in the main hull and communicating with the open sea, movable cylinders playing in said fixed cylinders and in open communication therewith, weighted pistons playing in said movable cylinders, and a power device controlling the movements of said pistons. 80

3. In a vessel the combination of a main hull, a vertical ballast-cylinder formed therein communicating with the open sea, a weighted piston in the form of a gun-platform playing in said cylinder and a power device controlling the movements of said piston. 90

4. In a vessel the combination of a main hull, a vertical ballast-cylinder formed therein communicating with the sea, a weighted piston in the form of a gun-platform playing in said cylinder, a telescopic cylinder having its piston connected to said platform and means supplying motive fluid to said telescopic cylinder. 95

5. In a vessel the combination of a main hull, a cellular flotation superstructure detachably secured water-tight to said hull, a fixed vertical ballast-cylinder formed in said hull communicating with the sea, a movable cylinder playing telescopically in said fixed cylinder through an opening in said superstructure, and a weighted piston in the form of a gun-platform playing in said cylinder, and a power device controlling the movements of said piston, whereby the main hull may be depressed below or raised on a level with the surface of the sea and the gun-platform simultaneously raised or lowered. 105

6. In a vessel a ballast-chamber consisting of a cylinder in communication with the sea, a weighted piston in the form of a gun-platform playing in said cylinder, and a power device controlling the movements of said piston, whereby the vessel may be lowered and the gun-platform simultaneously raised and vice versa. 110

7. In a vessel a main hull and a flotation superstructure secured water-tight thereon, a cylinder extending upward through the hull and said superstructure, a platform-piston playing in said cylinder and a power device controlling the movements of said piston. 120

8. The combination of a vessel, a gun-plat-

form and means simultaneously lowering the vessel and raising the platform and vice versa.

9. The combination of the main hull and the flotation superstructure secured water-tight thereon with a gun-platform normally within the main hull, and means simultaneously depressing the main hull below the sea-level and elevating the gun-platform into the superstructure.

10. The combination of the main hull, the

superstructure secured water-tight thereon, the telescopic ballast-cylinder with the gun-platform piston, and the power devices controlling the movements of said piston, with the automatically-controlled ballast-chambers.
